UNITED STATES PATENT OFFICE

FRANCISCO P. CORTÉS, OF NEW YORK, N. Y.

MEANS FOR OPERATING WINDOWS

Application filed August 29, 1927. Serial No. 216,038.

This invention relates to window operating arrangements and more particularly to arrangements whereby windows may be opened and closed, without touching the same and from a distance.

An object of the invention is to provide simple and efficient means for opening and closing windows.

Another object of the invention is to provide means for preventing binding of the windows during raising and lowering.

A still further object of the invention is to provide means for concealing a portion of the cord or other similar medium used in the invention.

According to the invention use is made of a pair of double pulleys secured to the frame of the window and through which cords fastened at suitable points pass to permit opening and closing of the window by pulling on one end of each of the cords. In order to prevent binding or sticking of the window during movement thereof the pulleys before mentioned are provided with rollers adapted to rotate against the window frame. It is also desirable that the pulleys be fastened to the window frame in such a manner as to permit accurate adjustment of the same relative to the casing of the window whereby the rollers carried by the pulleys may be positioned to bear against the casing of the window for the purpose before explained.

Other features and objects of the invention will become apparent by reference to the following detailed description read in the light of the accompanying drawings wherein,

Fig. 1 is a view showing the invention as installed upon the upper shafts of a window;

Fig. 2 is a side view partly in section of one embodiment of the double pulley utilized in the invention;

Fig. 3 is a section taken on the line 3—3 of Fig. 2;

Fig. 4 is a view similar to Fig. 2 of a modified arrangement of the double pulley, and

Fig. 5 is a vertical section illustrating the manner in which the pulleys are mounted upon the window itself.

Referring now to the drawings and par-

ticularly to Fig. 1, 10 indicates the frame of a window to which are secured a pair of double pulleys 11. A small single pulley 12 is fastened to the top of the window casing in any desired manner. A pair of cords 13 and 14 pass through the pulleys as indicated and have one of their ends fastened to any suitable portion of the casing as indicated at 15 and 16 respectively. As shown in Fig. 1 the cord 13 passes through the pulley 12, through each of the double pulleys 11 and is fastened to the top of the window casing as indicated at 15. Likewise the cord 14 passes through the double pulleys 11 and is fastened to the window casing as indicated at 16. Since the pulleys 11 are provided with double pulley rollers the cords are permitted to pass therethrough independently of each other.

Referring now to Figs. 2 and 3, the pulley 11 is composed of a framework 17 having mounted therein two pulley rollers 18 so arranged as to rotate about substantially the same axis but so mounted as to be separate from each other and also to be independently rotatable. The casing 17 is provided with slots 19 at both the top and bottom thereof through which pass bolts 20 for a purpose to be hereinafter explained. The casing 17 is also provided with a pair of extensions 21 between which a roller 22 is mounted for rotation in any desired manner as for example by means of a stationary shaft 23 passing through and secured to each of the extensions 21. The bolts 20 are provided at one end with a suitable thumb screw head 24 for permitting manual tightening and loosening thereof. As shown in Fig. 3 the threaded portion of the bolts 20 is of larger diameter than that portion of the rod passing through the slot 19. For this reason and on account of the fact that the thumb screw head 24 is also of larger diameter than that portion previously mentioned the rods are prevented from becoming disengaged from the slots 19 of the pulley.

The embodiment illustrated in Fig. 4 comprises a casing 17' of substantially one half the width of casing 17 but of such length as to permit the mounting therein of a pair of pulleys 18', one above the other in the same

vertical plane. The remaining parts of the pulley are substantially the same as those described in connection with the structure illustrated in Fig. 2 and Fig. 3, namely, a roller 5 22' mounted in projections 21', slots 19', bolts 20', and heads 24'.

In order that the pulley may be secured to the frame of the window suitable hollow screws 30 are permanently screwed into the 10 frame of the window. The method of securing the pulleys to a window frame is illustrated in detail in Fig. 5 wherein a pulley of the type shown in Fig. 4 is illustrated. It is to be understood, however, that the same arrangement is utilized in connection with a pulley of the type illustrated in Figs. 2 and 15 3. The bolts 20' may then be screwed into the threaded interior of the hollow screws 30 until the head 24' coming into contact with the casing 17' holds the pulley casing firmly 20 against the window frame. Since the casing is provided with the slots 19' the position of the pulley may be adjusted by loosening the bolts 20', shifting the pulley and then turning 25 the heads 24' until the pulley is firmly secured to the frame.

In order that that portion of the cords 13 and 14 extending between the pulleys 11 may be substantially concealed from sight and 30 also to prevent sagging of the same, telescoping members 32 similar to curtain rods are mounted upon hollow extensions 31 or 31' of the pulley casings depending upon the structure of pulley used. The telescoping members 32 may be closed hollow members or may have a portion thereof opened as is common 35 in the case of curtain rods.

For assembly it is necessary only to screw the hollow internally threaded screws 30 40 into the frame of the window one above the other near the edge of the frame. The pulleys are then secured to the frame in the manner before explained, care being taken to insure that the external guide rollers rest 45 against the window casing in such a manner as to prevent lateral movement of the window. The cords 13 and 14 may then be inserted through the respective pulleys and one end of each fixed to the casing as illustrated in Fig. 1.

Having assembled the device let it be assumed that the window is in the position illustrated in Fig. 1, that is, the sash is in its uppermost position. To open the window 55 it is merely necessary to pull the free end of cord 14. Since the opposite end of cord 14 is secured to the window casing, such pull will result in the lowering of the window. A pull exerted on cord 13 now causes the raising 60 of the window. During vertical movement of the window the external guide rollers rotating against the surface of the window casing prevent the window from binding 65 or sticking as heretofore has been found to occur when no arrangement is utilized to

prevent lateral movement of the window when a pull is exerted on either of the cords at the sides of the window. The telescoping members may be used to conceal the expanse of cords 13 and 14 lying between the 70 pulleys and also to prevent the cords from sagging down across the face of the window.

I claim:

1. The combination with a window of a pair of multi-roller pulleys mounted in a 75 casing securing to said window on opposite sides thereof, cords so arranged with respect to said pulleys that manipulation of the cords causes raising and lowering of said window, and means for preventing binding of said window against the window casing during movement thereof comprising guide rollers mounted between projections extending from the casing of said pulleys in peripheral contact with the window casing.

2. The combination with a window of a pair of multi-roller pulleys secured to said window on opposite sides thereof, said pulleys mounted in a casing, cords so arranged with respect to said pulleys that manipulation of the cords causes raising and lowering of said window, and means for preventing binding of said window against the window casing during movement thereof comprising guide rollers mounted between projections extending from the casing of said pulleys in peripheral contact with the window casing, and means for concealing from view and for preventing sagging of the expanse of cord between said pulleys comprising hollow telescopic members engaging and supported by hollow extensions from said pulley casings.

3. The window operating device comprising a pair of multi-roller pulleys and a guide roller in combination, a window and cords, 105 said pulleys and guide rollers secured to said window on opposite sides thereof, said pulleys adapted to cooperate with the cords to raise and lower the window, and the guide rollers adapted, by making peripheral contact with the window casing, to prevent the binding of the window against the window casing during the movement thereof, substantially as set forth.

4. The window operating device including 115 the combination with a window of a pair of multi-roller pulleys combined with a guide roller and adapted to be secured to said window on opposite sides thereof in such a way that when cords arranged with respect to 120 said pulleys and adapted on manipulation to raise or lower the window are operated, the guide rollers will make peripheral contact with the window casing being thereby 125 adapted to prevent binding of the window against the said window casing, substantially as described.

In testimony whereof, I have signed my name to this specification.

FRANCISCO P. CORTÉS.
